US00D551684S

(12) **United States Design Patent** (10) **Patent No.:** **US D551,684 S**
McClallen et al. (45) **Date of Patent:** **** Sep. 25, 2007**

(54) **EXCAVATOR BUCKET**

(75) Inventors: **Samuel L. McClallen**, Yorkville, IL (US); **Douglas R. Bye**, Hinckley, IL (US); **Jeremy D. Folkerts**, Lombard, IL (US); **Pandu R. Boyapally**, Aurora, IL (US)

(73) Assignee: **Caterpillar Inc**, Peoria, IL (US)

(**) Term: **14 Years**

(21) Appl. No.: **29/262,303**

(22) Filed: **Jun. 29, 2006**

(51) **LOC (8) Cl.** **15-03**

(52) **U.S. Cl.** **D15/32**

(58) **Field of Classification Search** **D15/10, D15/22-26, 28, 29, 32; D21/537; 414/722, 414/723, 686; 172/272-275; 403/324, 326, 403/315, 322.1; 37/403, 405, 408, 409, 411, 37/468, 444, 446, 443, 435, 379**

See application file for complete search history.

(57) **CLAIM**

The ornamental design for an excavator bucket, as shown and described.

DESCRIPTION

FIG. 1 is an isometric view of an excavator bucket showing our new design.

FIG. 2 is another isometric view of the excavator bucket.

FIG. 3 is a left side view of the excavator bucket.

FIG. 4 is a top view of the excavator bucket.

FIG. 5 is a bottom view of the excavator bucket.

FIG. 6 is a rear view of the excavator bucket; and,

FIG. 7 is a front view of the excavator bucket.

The right side view is the mirror opposite of the left side view in FIG. 3.

1 Claim, 7 Drawing Sheets
